General

UNITED STATES PATENT OFFICE.

MAXIMILIAN WEIL, OF NEW YORK, N. Y.

SPRING MOTOR.

Application filed April 4, 1921, Serial No. 458,345. Renewed August 22, 1923.

To all whom it may concern:

Be it known that I, MAXIMILIAN WEIL, a citizen of the United States, and resident of New York city, in the county of New York and State of New York, have invented certain new and useful Improvements in Spring Motors, of which the following is a specification.

My present invention relates in its more specific applications to spring motor driving mechanisms for phonographs although many of the features of the invention are broadly applicable to spring power or equivalent mechanisms regardless in what relation they are employed and regardless what they serve to propel.

The invention is concerned with specific adaptations of certain features of the invention disclosed and broadly claimed in my copending application, Serial No. 396,211, filed July 14, 1920.

In common with my said prior invention, the present invention has for one of its objects the provision of a spring power mechanism in which the effect of a rupture of a spring unit is quickly eliminated without inconvenience so that even after such rupture the mechanism can be continued in use until such time as replacement of the broken unit can be effected.

One known form of spring mechanism for phonograph motors comprises a pair of coaxial spring drums, the springs being connected in series at their inner ends by means of a sleeve extending into both drums, winding torque being applied at one of the drums and the power delivered to the driven mechanism from the other drum. In this form of mechanism, if either spring breaks or becomes disconnected the motor is inoperative.

According to one feature of my invention, mechanism of the construction last referred to is equipped with a coupling means arranged to establish a direct mechanical connection between the sleeve and one of the drums for operation of the apparatus with but one of the springs operatively connected. In the preferred embodiment the coupling means is arranged to be readily set for cutting either of the springs out of operation and this regardless whether the spring is

broken or intact. The coupling member is preferably in the form of a clutch mounted upon the sleeve and disposed in the space between the drums, and having teeth for cooperation with corresponding teeth upon the drums.

In the accompanying drawings, in which is shown one of various possible embodiments of the several features of this invention,

Fig. 1 is a view in longitudinal section of the preferred embodiment of the invention, Fig. 2 is a transverse sectional view taken along the line 2—2 of Fig. 1, and;

Figs. 3 and 4 are detail sectional views taken on lines 3—3 and 4—4 respectively of Fig. 1.

Similar reference characters refer to similar parts throughout the different views of the drawings.

Referring now to the drawings, I have shown at 1 a fragment of a motor board of a phonograph to the bottom of which is secured the spring motor unit 2. This motor is shown by way of illustration as of the two-spring type although the invention is applicable to motors embodying three or more springs. The construction of the motor in its general features is of a familiar type, which taken by itself is not claimed herein.

The known elements of the construction comprise a main frame 3 including a pair of standards 4 extending downwardly from the motor board when the motor is in position as shown. Through the standards extends a dead shaft or supporting rod structure 5. Encircling the supporting rod near the right end of the sleeve 9 is a bushing 6 to which is rigidly connected, preferably by being forced thereover the cover plate 7 of a drum 8, the length of the drum extending over the end of a sleeve 9 mounted upon the supporting rod structure 5. The inner end or bottom 10 of the drum 8 has preferably a washer 11 held in place in a manner to be described below to prevent escape of lubricant between the drum and the sleeve 9.

At the left end of sleeve 9 is a short sleeve 12 encircling the supporting shaft which is formed rigid and preferably integral with the driving or transmission gear 13, the lat-

ter also constituting an end or cover for the second drum 14. The drum 14 extends coaxially with the first drum 8 and inwardly over the left end of the sleeve 9 and has at 5 its inner end 23 a washer 15 similar to washer 11, a space 16 being left between the two drums.

As shown in the drawings, the springs 17 and 18 one in each drum are coiled about the 10 sleeve 9, and each has preferably a reclutching power transmitting connection 19 with the sleeve, for purposes which will appear more fully below, the other end of the spring being secured as at 20 to the drum 15 enclosing it. The connection 19 comprises a shoulder 50 cut into the sleeve and extending the width of the spring, the spring having an inwardly bent hook 15 at its inner end to fit against said shoulder substantially 20 as in patent to Maynard No. 160,109. By this construction it will be seen, an effective driving connection is provided for one direction of rotation and the end of the spring will in effect ratchet over the shoulder for the opposite direction of rotation without breaking the spring. The spring 25 automatically reconnects or reclutches when rotation in the correct direction is resumed.

Winding mechanism 21 of any appropriate construction, the details of which are not here involved is mounted upon bushing 6. A desirable form of such mechanism is described in my copending application, Serial No. 396,211. In this construction it will 30 be seen that the two springs 17 and 18 are connected in series between the winding mechanism 21 and the transmission gear 13, the sleeve 9 serving as the direct power connection between the inner ends of the 35 springs. I will designate drum 14 with the parts enclosed thereby spring unit No. 1, and the other drum with enclosed parts as 40 spring unit No. 2.

Any appropriate transmission mechanism 45 may be employed for delivering the power from gear 13 to the turn table spindle (not shown). By preference the mechanism shown in my copending application, Serial No. 389,803, filed June 18, 1920, will be used.

According to a preferred form of my invention, I provide a clutch 22 encircling the sleeve 9 and situated between the adjacent drum ends 10 and 23. The clutch is arranged to establish a rigid connection 50 between the sleeve 9 and the drum 14 when in one extreme position, thereby cutting out of operation the coil spring unit No. 1 and establishing a rigid connection between spring unit No. 2 and the transmission gear 13. In 55 the second extreme position, the clutch establishes a rigid connection between the sleeve and the drum 8 thereby cutting out of operation coil spring unit No. 2 and establishing a rigid connection between the 60 spring unit No. 1 and the winding mecha-

nism 21. In the intermediate or neutral position shown in the drawings, the clutch element is out of operation and the two springs will function as in the ordinary construction.

Preferably the setting of the clutch is effected by a shifting of the supporting rod or dead shaft 5, although shifting means separate and distinct from the supporting rod may be provided. For this purpose the 70 clutch member 22 is preferably provided with a pair of diametrically opposite pins 24 threaded therewith as at 25 extending radially inwardly thereof each through a corresponding longitudinal slot 26 in the sleeve 80 9, the supporting rod structure being formed with a circumferential groove 27 into which the inner ends of said pins extend. Thus, when the supporting rod 5 is shifted in either direction, the clutch 22 will be shifted thereby 75 in the corresponding direction to establish a rigid connection between the sleeve and the drum with which it is brought into coaction.

Although the groove structure 27 may be 80 cut into an integral rod of substantially the inner diameter of sleeve 9, I have shown an embodiment in which a pair of sleeves 28 and 29 of appropriate outer diameter are fitted over the opposite ends of the rod 5 and pinned thereto as at 30, the adjacent ends 31 and 32 of said sleeves being adjacent 85 to the pins 24. The rod structure can thus be formed of standard rod and standard tubing and at small expense.

The clutch is preferably provided with 90 one set of equidistant teeth 33 at one end and a second set 34 at the opposite end. The drum ends 10 and 23 adjacent the clutch are 95 respectively provided with complementary tooth structures 35 and 36 for cooperation 100 with the teeth at the adjacent end of the clutch member. The tooth structure 35 preferably comprises an annular clutch plate 37 secured to the bottom or end 23 of the drum 14 by screws as at 38 and having teeth 35 105 projecting from the inner periphery 4 for cooperation with the set of teeth 33. The plate 37 is preferably beveled at its inner periphery and below the teeth thereon as at 40 to securely retain in place the washer 15 110 above referred to for preventing egress of lubricant. A similar construction is formed at the adjacent end or bottom of the other drum 8.

By the construction described it will be 115 seen that the clutch member 22 is free to rotate with respect to the supporting rod member 5 but not free to move longitudinally with respect thereto, and that it is free to be displaced along the sleeve 9 but must rotate 120 therewith as a unit.

For operating the clutch member I prefer to employ a construction generally similar to that disclosed in my copending application, Serial No. 418,727, filed October 22, 130

1921. Briefly, this construction comprises a lever 41 pivoted to lug 42 cast integrally with the frame structure 3 and having an operating handle 43 projecting above the 5 motor board 1 and pivoted at its lower end as at 44 to the supporting rod 5. As in the copending application, notches are formed in a cover plate 45 to lock the operating arm and consequently the supporting rod in any 10 of the various settings that may be required in use. In the present case there will be three notches 46, 47 and 48, notch 47 corresponding to the neutral position of the clutch, and notches 46 and 48 one to each of 15 the operative positions thereof.

In operation, assuming that unit No. 2 has been broken, to set the device for operation, the lever handle 43 is shifted to move the rod 5 to the right, the latter carrying with 20 it the clutch 22, the teeth 34 of which will enter into mesh with the clutching plate construction upon drum 8, in effect, a mechanical short-circuit about the broken spring unit No. 2. When winding torque is now 25 applied through the winding handle (not shown) the same will be transmitted through the drum 8 to the clutch 22, to the sleeve 9 and from the latter to spring 17. Since the brake mechanism (not shown) prevents rotation 30 of transmission gear 13 and of drum 14 to which the outer end of spring 17 is secured, the said outer end will remain stationary while the inner end is moved about the axis, and winding, accordingly, takes 35 place. The inner end of the spring is held against unwinding by the restraining action of the winding mechanism 21 substantially in the usual manner. When the brake mechanism is released, the single operative 40 driving spring in its expansion will, therefore, furnish the driving energy.

When a rupture or unhooking occurs, the user, of course, does not know whether it is unit No. 1 or unit No. 2 that has become inoperative. If, as above assumed, the spring unit No. 2 breaks and the user thereupon shifts the lever to move the rod toward the left instead of toward the right, thus short-circuiting the single intact spring, rotation 50 of the winding handle will, of course, be ineffective for storing energy in the motor. The user not encountering the usual resistance to winding will now shift the lever 41 in the opposite direction until it is locked 55 in the other extreme notch in cover plate 45 and the device will then function as above set forth.

Should the spring unit No. 1 become ruptured or disconnected, the clutch should be 60 moved toward the left by shifting the lever 41 toward the right, thus bringing the clutch teeth 33 into mesh with the teeth on plate 37, thereby in effect, short-circuiting the spring 17. The winding of the unbroken 65 spring unit No. 2 can now be effected by

rotation of the winding handle, the winding torque being transmitted from the drum 8 to spring 18. The sleeve 9 to which the inner end of spring 18 is secured is held against rotation, since it is locked to drum 70 14 by clutch 22, the drum 14 being retained against rotation by transmission gear 13 which in turn is held by the action of the braking mechanism (not shown). When the brake is released, the single operative 75 spring reacts against stationary drum 8 in its expansion and transmits power through sleeve 9, clutch 22, drum 14 and transmission gear 13 to the driven mechanism.

Although the clutch teeth 33 and 34 are 80 preferably beveled at their ends as at 50 to facilitate mesh with the clutch plates, it is desirable to rotate the winding crank through a small angle while shifting the clutch. It will be apparent that the likelihood 85 of butting of clutch teeth with those on a clutch plate is thus obviated.

When either of the springs breaks, the restraining force on the intact spring is suddenly released and the latter rapidly expends its stored energy. As distinguished from constructions in which the spring does not automatically reconnect should it become disengaged, unhooking of one of the springs upon rupture of the other causes no 90 inconvenience in my construction, for, as heretofore indicated, such detached spring would automatically reconnect with the sleeve 9 upon winding, after the operator 95 has short-circuited the ruptured spring. 100

Thus, I have provided a construction in which, upon rupture of either spring, whether or not the other has thereby become unhooked, it is merely necessary to shift lever 43 in the appropriate direction and to 105 wind the mechanism in the usual manner in order to unfailingly restore the motor for operation upon the intact spring or springs. Obviously, the reclutching connection set forth could be employed in the construction 110 of my copending application, Serial No. 396,211, above referred to.

It will thus be seen that by means of a simple modification of certain details of a familiar form of phonograph motor, I 115 achieve the desirable results above noted. Substantially, the only changes made in the familiar construction are the provision of the slots 26 in the sleeve 9, the provision of the clutch construction 22 and of the clutch 120 plate constructions 37 and the simple modification of the supporting shaft construction either by cutting a circumferential groove centrally thereof or by employing the sleeves 28 and 29 as pointed out. The operating mechanism connecting the shifting rod to the top of the motor board as seen, is made at small expense from standard gauge stock.

Many of the beneficial characteristics 125 130

pointed out in my copending application, Serial No. 396,211 are inherent in the invention of the present application.

The motor can be set for operation by any inexperienced person, even by a child, there being no occasion to touch or even to inspect the motor.

The operating lever by its co-action with one of the notches in the cover plate 45 10 serves to retain the shifting rod and with it the clutch against displacement from any position in which it is set.

Although the motor can be operated to advantage according to the method above indicated that is, by shifting the clutch, in order to eliminate a spring upon rupture thereof, it is preferable not to set the clutch in the neutral position when the motor is new, or at any other time, but to place it 20 from the outset into cooperation with either drum 8 or drum 14 so that the motor operates at all times on only one spring, the unused spring not being used and being maintained in perfect condition in reserve to be 25 cut into operation only when the first spring breaks down. Thus, my present invention also provides a selective arrangement affording a choice as to which spring or springs are to be kept in use.

30 As in the case of my copending application, Serial No. 396,211, it will be obvious that my invention might be carried out in a construction in which it would be possible to use only one of the springs at a time, 35 there being no neutral position for operation with both springs concurrently. This idea might be carried out in a simple manner by lengthening the clutch 22 or the clutch teeth 33 and 34 so that one set must always be in 40 mesh.

Although the invention has been shown and described as applied to a power unit of the two-spring type, it will be understood that the idea can be readily applied to drums 45 embodying three or more springs, in such manner that any one of the plurality of springs can be eliminated from operation either when intact or when ruptured, or that any one of said plurality of springs can be 50 maintained in operation, the others being eliminated from operation.

No increase in length or diameter of 55 spring motors results from embodying my selective mechanism therein, since in the preferred form, the clutch is disposed between successive drums and the supporting rod serves as a transmission to the clutch from the manual operating means external of the motor. The motor with my selective 60 mechanism embodied therein is a single self-contained unit that can be applied to the phonograph with the same facility as motors that do not embody my invention.

It will be apparent that, if desired, automatic means might be provided for shifting

the clutch instead of the manual means shown.

The above description has been limited to the preferred application of my invention to certain types of phonograph motors but is, of course, broadly applicable in any relation where such general type of motor may be useful, as, for instance, in the operation of signal apparatus.

As in the case of my copending application, Serial No. 396,211, it is to be understood that in its broader aspects the present invention might also be carried out in a spring construction having associated therewith means for substituting a relatively rigid connection for a section of the spring mechanism, whether such spring section is intact or broken and it is also to be noted that this rigid construction might be embodied in various forms of couplings other than the clutch arrangement shown.

I claim:

1. In apparatus of the character described, in combination, a frame, a power plant mounted thereon, comprising a plurality of driving springs, winding means for delivering energy to said springs, a connection for delivering stored energy from said springs, and coupling means upon said power plant and exposed between said springs for establishing a driving connection about one of said springs.

2. In apparatus of the character described, in combination, a power plant comprising a pair of drums, coil springs, one in each of said drums, a member extending into said drums for connecting the inner ends of said springs in series, and coupling means for establishing a direct connection between said member and one of said drums in lieu of the corresponding spring.

3. In apparatus of the character described, in combination, a power plant comprising a pair of coaxial drums, coil springs, one in each of said drums, a winding connection and an energy delivering connection at opposite ends of said power plant, means extending coaxially into said drums for connecting said springs in series, and means exposed between said drums for establishing a rigid connection about one of said springs.

4. In apparatus of the character described, in combination, a power plant comprising a pair of drums, a pair of coil springs, one in each drum, a winding connection at one end of said power plant and a power delivery connection at the other end of said power plant, means extending into said drums and coaxially thereof for connecting said two springs in series, and a coupling device between the said drums for establishing a rigid connection about either of said springs.

5. In apparatus of the character described, in combination, a shaft, a pair of

drums mounted thereon, a pair of coil springs one within each drum and secured thereto at its outer end, a connector joining the inner ends of said springs, and means for rigidly joining said connector to either of said drums.

6. In apparatus of the character described, in combination, a supporting shaft, a sleeve floatingly mounted thereon, a pair of drums, a pair of coil springs one in each of said drums, each connected at its inner end to said sleeve and at its outer end to the corresponding drum, and means disposed adjacent said sleeve and between said drums and arranged to be actuated for establishing a rigid connection between said sleeve and either of said drums.

7. In apparatus of the character described, in combination, a shaft, a sleeve floatingly mounted thereon, a pair of drums floatingly mounted upon said shaft and extending toward each other from opposite ends of said sleeve, said drums being spaced from each other at their adjacent ends and forming a liquid tight connection with said sleeve at said ends, a spring in each said drum connecting the same to said sleeve, and a coupling member arranged to be shifted along said sleeve for establishing a rigid connection between either of said drums and said sleeve.

8. The combination set forth in claim 7 in which the coupling means has a neutral position and is arranged to be shifted in either direction for cooperation with either of said drums.

9. The combination set forth in claim 7 in which the coupling member is mounted upon the sleeve, rotatable therewith and slidable thereon.

10. In apparatus of the character described, in combination, a supporting shaft, a sleeve floating thereon, a coupling member surrounding said sleeve, slidable thereon but limited against rotation with respect thereto, a pair of drums extending over opposite ends of said sleeve and toward said coupling member, springs in said drums connecting the latter to said sleeve, said coupling member having teeth at its opposite ends and a conformation upon said drums for cooperation with the corresponding coupling member teeth, whereby upon shifting said coupling member in either direction, a rigid connection will be established between said sleeve and one of said drums.

11. In apparatus of the character described, in combination, a sleeve, a pair of drums extending over opposite ends of said sleeve, springs within said drums connecting said drums to said sleeve, a clutch member surrounding said sleeve between said drums and a shifting rod extending through said sleeve and connected to said clutch member for shifting the latter in one direction to

establish a rigid connection between said sleeve and one of the drums.

12. In apparatus of the character described, in combination, a power unit comprising a pair of coaxial drums spaced from each other, a clutch member between said drums, springs in said drums, a connector for joining said springs to operate in series, and means operable from the exterior of said power unit to shift said clutch in either direction for establishing a rigid power connection between said connector and either of said drums.

13. In apparatus of the character described, in combination, a supporting rod structure, a groove therein, a sleeve surrounding said rod, a clutch member surrounding said sleeve, a stop extending from said clutch member through a longitudinal slot in said sleeve and into said groove, drums floatingly mounted at opposite sides of said clutch and having teeth adapted to cooperate with teeth on said clutch, whereby upon longitudinal shifting of said supporting rod, said clutch will be shifted along said sleeve to establish a direct driving connection between said sleeve and one or the other of said drums.

14. In apparatus of the character described, in combination, a supporting rod having a pair of sleeves rigidly secured thereto, the adjoining ends of said sleeves being spaced from each other, a sleeve floatingly mounted upon said secured sleeves and having a pair of elongated longitudinally extending slots, a clutch member encircling said sleeve, having teeth at its opposite ends, said clutch having a pair of pins threaded thereinto and extending through said elongated slots and between the adjoining sleeve ends upon said supporting rod, a pair of drums floatingly mounted upon said supporting rod structure at the opposite ends of said sleeve and extending inwardly toward each other, and sets of teeth upon the adjacent ends of said drums, with either of which the corresponding clutch member teeth are adapted to be meshed upon shifting of the supporting rod in the corresponding direction.

15. In apparatus of the character described, in combination, a power plant involving a plurality of coil springs, anchoring means for the outer ends of the springs, anchoring means for the inner ends of the springs, means for altering the mechanical connections for operation of the motor with less than all of said springs operatively connected, one of the anchoring means for each of said springs being automatically reclutching, whereby should any spring disconnect upon rupture of another, it will reconnect to permit operation of the motor after the said mechanical connections are altered.

16. In a phonograph motor, in combination, a power plant comprising a plurality of coaxial coil springs, connected in series, winding means for delivering energy to said power plant, torque transmitting means for delivering energy from said power plant, coupling means for establishing a mechanical short-circuit about a broken spring, a releasable power connection for an end 10 of each of the springs, said connection being constructed and arranged to automatically resume operative position, whereby should any spring disconnect before rupture of another, it will reconnect to permit operation 15 of the motor after said short-circuit is established.

17. In apparatus of the character described, in combination, a power plant comprising a pair of coaxial spring units arranged side by side, winding means at one end of the power plant, torque transmitting means at the other end of the power plant, coupling means for establishing a mechanical short-circuit about a broken spring, 25 drum means to which the outer ends of said springs are secured, sleeve means having a

power transmitting connection to the inner ends of said springs, the connection of said springs at said sleeve means being automatically releasable and being constructed 30 and arranged to automatically reconnect, whereby should any spring disconnect before rupture of another, it will reconnect to permit operation of the motor after said short-circuit is established.

18. The combination set forth in claim 6 in which the connection of the springs at their inner ends to the sleeve, comprises an inturned spring end cooperating with a shoulder in the sleeve extending substantially the width of the spring, the shoulders for the two springs facing in opposite directions, whereby upon rupture of a spring, the remaining spring will remain intact and will become automatically reanchored 40 should it be disengaged for operation of the motor.

Signed at New York city, in the county of New York and State of New York this 29th day of March, A. D. 1921.

MAXIMILIAN WEIL.
